UNITED STATES PATENT OFFICE.

CHARLES B. MARTIN, OF BARTLESVILLE, OKLAHOMA.

PUMP.

Application filed October 2, 1923, Serial No. 666,114. Renewed May 1, 1928.

This invention relates to pumps and more particularly to well pumps.

The primary object of the invention is to provide a double acting deep well pump designed to raise about 70% more liquid from a deep well than the ordinary single acting pump.

A further object of the invention is to provide a deep well pump constructed to permit the removal of the parts in two operations.

Another object of the invention is to furnish a deep well pump consisting mainly of tubing, ball valves and packing, and constructed to permit ready assembling or dismantling of the parts to facilitate repairing or replacements.

With the foregoing objects outlined and with other objects in view which will appear as the description proceeds, the invention consists in the novel features hereinafter described in detail, illustrated in the accompanying drawings and more particularly pointed out in the appended claims.

Referring to the drawings:—

Fig. 1 is a longitudinal sectional view of the improved pump illustrated in the position which it occupies in a well casing.

Fig. 2 is an enlarged vertical sectional view of the upper portion of the pump.

Fig. 3 is a similar view of the intermediate portion of the pump.

Fig. 4 is a similar view of the lower portion of the pump.

Fig. 5 is a horizontal sectional view taken on the line 5—5 of Fig. 4.

Fig. 6 is a similar view taken on line 6—6 of Fig. 2.

Fig. 7 is a horizontal sectional view taken on line 7—7 of Fig. 4.

Referring to Figs. 1 and 4, the lower portion of the pump consists of an ordinary gas anchor 1 having internal threads at its upper end connected to external threads at the lower end of the pump casing 2. Arranged within the lower portion of the casing 2 is a stand valve housing 3 having, as shown in Figs. 4 and 7, a plurality of longitudinally extending peripheral grooves or channels 4 which extend upwardly from the lower end 5 of the housing to ports 6 arranged near the upper end of said housing. These ports lead into the bore 7 of the housing. Longitudinally extending peripheral grooves or channels 8 also extend downwardly from the upper end 9 of the housing to ports 10 arranged near the lower end of the housing, and these

ports lead into an annular chamber 11 communicating with the bore 7 of the housing. These channels and ports are adapted to convey the liquid pumped, in a manner herein- 60 after described.

The bore 7 extends entirely through the housing 3 and is provided at its lower end with a conical surface 12 to receive a correspondingly shaped nut 13 screwed on the lower end of a short pipe 14. The conical surface 12 limits the downward movement of the nut 13 and of the pipe 14 to which said nut is threaded.

Packing rings 15 surround the pipe 14, rest 70 on the nut 13 and prevent the passage of liquid between the bore 7 and the pipe 14, at the place where the pipe 14 is located. Arranged above the pipe 14 is a tube 16 having internal threads at its lower end which engage external threads at the upper end of the pipe 14. The tube 16 has an internal shoulder 17 against which a valve seat 18 is forced by the upper end of the pipe 14. The tube 16 houses a ball valve 19 and is provided with ports 20 communicating with the annular chamber 11. At this point it will be noted that liquid passing up the pipe 14 displaces the valve 19 and passes through the ports 20 and 10 into the channels or grooves 8. 80

A conduit 21 is arranged above the tube 16 and has a solid extension 22 at its lower end provided with external threads connected to internal threads on the tube 16. The solid extension 22 prevents liquid from passing from the interior of the tube 16 to the interior of the conduit 21. Said conduit is provided with a plurality of outwardly extending annular flanges 23 and 24 which form an annular groove 25 on the conduit adapted to communicate with the ports 6 in the housing and ports 26 in the conduit. Packing rings 27 are arranged between the upper end of the tube 16 and the shoulder 24 and function to prevent the passage of liquid from the chamber 11 to the groove 25. The upper end portion of the conduit 21 supports a valve seat 28 which is clamped in position by a valve cage 29 in threaded engagement with the conduit 21. The valve cage encloses a ball valve 30 and is provided with radially arranged elongated slots 31 and a threaded aperture 32, for purposes hereinafter described.

The upper end of the bore 7 of the housing 3 has internal threads which are connected to the external threads at the lower end of a

pump barrel 33. As best shown in Figs. 1, 2 and 3, this pump barrel extends upwardly and has external threads at its upper end secured to a ring 34, see particularly Fig. 2. In this figure it will be also seen that the barrel is provided near its upper end with a number of spaced radially disposed apertures or ports 35 which place the interior 36 of the barrel 33 in communication with an annular chamber 37 which is located between the casing 2 and the barrel 33 and communicates at its lower end with the channels 8 of the housing 3. The barrel is provided near its upper end and above the ports 35 with internal annular grooves 38 which receive packing rings 39. The extreme upper end of the barrel has an internal conical socket 40 in frictional engagement with a conical head 41 provided at the upper end of a sleeve 42. This sleeve has a shoulder 43, and the packing rings 39 are forced towards this shoulder by means of a nut 44 at the lower end of the sleeve. At this time it is to be noted that when pressure is exerted on the lower end of the sleeve 42 and on the nut 44 in an upward direction the nut 44 will lift the packing rings 38 with the sleeve, as the head 41 of the latter moves out of the conical socket 40.

A hollow pump rod 45 extends through the sleeve 42, and, as shown in Fig. 3, its lower end is in threaded engagement with a hollow piston 46. Said piston carries a number of metal rings 47 and packing cups 48, all held in place by a nut 49 at the lower end of the piston. The pump rod 45 extends upwardly through a valve member 50, see Fig. 2, and the rod slides through this member 50 in the operation of the pump. The member 50 consists of a short section of pipe having a threaded head 51 which forces a spring 52 in the pipe against packing glands 53 that bear on packing rings 54. The lowermost packing ring bears against a packing gland 55 which in turn rests on a ring 56 having radially disposed apertures 57, only one of which is shown in the drawing, but in the actual construction illustrated, there are three of these recesses 57 equally spaced around the ring 56. Arranged below the ring 56 is a screw head 58 having a valve head 59 at its lower end. This valve head is preferably formed of leather or the like and is adapted to seat on the head 41 of the sleeve 42 in order to close ports 60 which extend through said head and communicate with the interior chamber 36 of the pump barrel 33. In operation, it is to be understood that the pressure of the liquid passing upwardly through the ports 60 intermittently moves the member 50 and its connected parts upwardly in order to open the ports 60 and permit the liquid to pass from the chamber 36 into a chamber 61 surrounding the member 50. For the purpose of moving the member 50 downwardly toward the head 41, a plurality of screws 62 extend through the nut

58 and into the head 41. Each one of these screws is surrounded by a spring 63 which pushes against the head of the screw and against the nut 58. These screws are equally spaced around the nut 58 as shown in Fig. 6 70 and their springs 63 will push the member 50 with the valve head 59 toward the head 41 in order to close the ports 60.

In the construction shown in the drawing, which is in practical operation, the annular ring 34 is threaded to the lower end of a casing extension 64 that is welded at 65 to the upper end of the pump casing 2. The upper end of this extension is reduced in size and is connected by a threaded collar 66 to the lower end of the pump tubing 67, through which the liquid is forced to the top of the well.

As best shown in Fig. 2, the upper end of the pump rod 45 is in threaded engagement 85 with a nipple 68 which supports a valve seat 69 held in place by a slotted valve cage 70 that houses a ball valve 71 and is provided at its upper end with a threaded stud 72, the latter being adapted to be connected to any form of operating rod, not shown in the drawings.

In using the pump, the gas anchor 1, casing 2, housing 3, pump barrel 33, casing extension 64, collar 66 and pump tubing 67 are to be arranged permanently in the well and the stand valve at the lower end of the pump may be first inserted into the housing 3, after which the pump rod carrying the member 50, the piston 46 and sleeve 42 may be dropped 100 into the well.

In operation, the pump rod 45 is reciprocated and assuming that the piston 46 is moving downwardly, suction will be created in the chamber 36 above the piston and this suction will tend to create a vacuum in the ports 35, chamber 37, channels 8, and the ports 10 and 20, so that the valve 19 will raise from its seat and permit the passage of liquid upwardly through the pipe 14, ports 20 and 10, channel 8, chamber 37 and through ports 35 into the chamber 36. At the same time liquid which has previously been drawn into the chamber 73 of the barrel, below the piston, will be forced upwardly through the hollow piston 46, pump rod 45, past the ball valve 71 through the slots of the cage 70 and into the well tubing 67. It will thus be seen that on the downward stroke of the pump, liquid will be forced upwardly through the tubing 115 piston 46, pump rod 45, past the ball valve 71 through the slots of the cage 70 and into the well tubing 67. Then at the commencement of the upward stroke, the rising of the piston 46 will tend to create a vacuum in the chamber 73, thus seating the ball valve 71 and at the same time raising or unseating the ball valve 30, so that liquid will pass upwardly through the channels 4, ports 6, groove 25, ports 26 and the slots 31 into the chamber 73. At the same time the liquid which was drawn into the chambers 36 and 37 on the downward stroke 120 130

is placed under pressure and this pressure causes the valve 19 to close the pipe 14. Therefore as the liquid cannot escape through the pipe 14 it must pass up through 5 the sleeve 42 and ports 60 and it will exert sufficient pressure on the valve 59 to lift the member 50 and permit the liquid to flow upwardly through the chamber 61 into the tubing 67 of the pump. It will thus be seen 10 that both on the down stroke and up stroke of the piston, liquid is drawn in and forced out of the pump and into the pump tubing 67, and it has been found from actual practice that this pump forces about 70% or more 15 liquid than a single acting pump of the same size.

When it is desired to withdraw the parts from the casing, the sucker rod is raised and this will cause the pump rod 45 to rise, and 20 as the latter moves upwardly, the upper end of the piston 46 will strike the lower end of the sleeve 42 and the nut 44, so that the sleeve, nut and packing 39 will rise with the piston. After these parts have been drawn to the top 25 of the well, a fishing rod may be inserted and its lower threaded end may be threaded into the socket 32 of the stand valve, and when the fishing rod is raised, the entire stand valve will also be elevated.

30 From the foregoing it is believed that the construction, operation and advantages of the invention may be readily understood by those skilled in the art, and it is apparent that changes may be made in the details disclosed without departing from the spirit of the invention as expressed in the claims.

What is claimed and desired to be secured by Letters-Patent is:

40 1. A pump including a casing provided at its lower end with a stand valve structure, a barrel arranged in said casing and extending to said stand valve structure, said stand valve including a plurality of valves for con-

trolling the admission of fluid into the interior of said barrel and to the chamber between the barrel and casing, ports provided in the upper portion of the barrel and placing the interior of the barrel in communication with said chamber, a hollow pump rod having a piston arranged in said barrel, means 45 closing the space between the pump rod and the upper end of said barrel and provided with ports to permit the passage of fluid from the interior of the barrel to the upper portion of the casing, a sliding valve normally closing 50 the last mentioned ports, and a valve associated with the pump rod for controlling the passage of fluid through the latter, the upper end of said barrel being provided with an internal conical surface, the means closing 55 the space between the upper end of the barrel and the pump rod being provided with a corresponding surface to permit the withdrawal of said means from the barrel when the piston is raised, said means including a 60 sleeve provided with a head, a nut arranged on said sleeve, and packing surrounding the sleeve and bearing against the inner surface 65 of said barrel.

2. A pump as claimed in claim 1 in which 70 the sliding valve is connected to the means closing the space between the barrel and pump rod, by rods surrounded by springs tending to force the sliding valve toward the ports which it controls.

75 3. A pump as claimed in claim 1 in which the sliding valve consists of a sleeve having closed ends, packing rings arranged in the sleeve and bearing against said pump rod, a spring in the sleeve bearing on said packing 80 rings, and yielding means connecting the sliding valve to the means closing the space between the pump rod and said barrel.

In testimony whereof I affix my signature.

CHARLES B. MARTIN.
